ABSTRACT OF THE DISCLOSURE

Surplus in a tobacco stream which is conveyed in the groove of a suction conveyor is trimmed off in a plurality of stages. The resulting filler rod is transferred onto a further conveyor and is wrapped into cigarette paper. The tobacco stream in the groove of the suction conveyor is compacted by stationary or rotary mechanical compacting means.

CROSS-REFERENCE TO RELATED APPLICATION

This is a division of my application Ser. No. 112,076, filed May 23, 1961, now Pat. No. 3,316,917, granted May 2, 1967. Said application Ser. No. 112,076 is a division of Ser. No. 853,273, filed Nov. 16, 1959 and now abandoned.

BACKGROUND OF THE INVENTION

The present invention relates to the manufacture of tobacco-containing products, and more particularly to the manufacture of cigarettes or like rod-shaped articles wherein a tubular wrapper surrounds a filler of tobacco-containing material. Still more particularly, the invention relates to improvements in apparatus for producing a tobacco rod of uniform cross section and, if desired, of uniform density.

Presently known methods and apparatus for the production of wrapped tobacco rods are not entirely satisfactory because the density of the tobacco rod is not constant along its entire length. The difficulties are due less to the organic nature of tobacco and to its often varying physical properties than to the nature of treatment to which the tobacco is subjected in conventional cigarette making machines. During each transfer from conveyor to conveyor, the tobacco is subjected to treatment which interferes with the formation of a stream having the desired structure. In some instances, the transfer from conveyor to conveyor can adversely affect the coherence between the particles of the stream which has been formed on the preceding conveyor. For example, when a tobacco fleece is removed from a carding roller, the fibers may be torn apart to such an extent that the structure of the stream is altered considerably or the fleece-like form is destroyed before the stream reaches the rod forming parts of the apparatus.

SUMMARY OF THE INVENTION

It is an object of the present invention to provide an apparatus which can separate a continuous stream of tobacco from a tobacco mass which travels in an endless path and converts the thus separated continuous stream into a tobacco rod.

Another object of the invention is to provide a tobacco rod forming apparatus wherein the conversion of

a tobacco stream into a rod of desired cross section is carried out in a plurality of stages.

A further object of the invention is to provide an apparatus wherein the tobacco is subjected to requisite compression prior to formation of the rod.

An additional object of the invention is to provide a tobacco rod forming apparatus wherein the removal of surplus tobacco from a tobacco stream takes place in plural steps.

10 A concomitant object of the invention is to provide very simple and efficient trimmers for use in an apparatus of the above outlined characteristics.

15 The novel features which are considered as characteristic of the invention are set forth in particular in the appended claims. The improved tobacco rod producing apparatus itself, however, both as to its construction and its mode of operation, together with additional features and advantages thereof, will be best understood upon perusal of the following detailed description of certain 20 specific embodiments with reference to the accompanying drawing.

BRIEF DESCRIPTION OF THE DRAWING

FIG. 1 is a diagrammatic elevational view of an apparatus which embodies one form of my invention;

25 FIG. 2 is an enlarged fragmentary horizontal sectional view as seen in the direction of arrows from the line II—II of FIG. 1;

FIG. 3 is a fragmentary elevational view of a second apparatus;

FIG. 4 is a diagrammatic elevational view of a third apparatus;

FIG. 5 is a fragmentary transverse vertical section as seen in the direction of arrows from the line V—V of FIG. 4;

30 FIG. 6 is a fragmentary sectional view similar to the view of FIG. 2 but further showing a rotary mechanical compacting member for tobacco in the groove of the first conveyor means;

35 FIG. 7 is a fragmentary sectional view of another apparatus wherein the rotary compacting member of FIG. 6 is replaced with a stationary compacting member;

40 FIG. 8 is a fragmentary sectional view of a further apparatus which utilizes two trimmers, the second of the trimmers being shown in the process of removing the remainder of tobacco surplus from the groove of the first conveyor means;

FIG. 9 is an enlarged section as seen in the direction of arrows from the line IX—IX of FIG. 1;

45 FIG. 10 is a section as seen in the direction of arrows from the line X—X of FIG. 9; and

FIG. 11 is a fragmentary end elevational view of a suction wheel which can be used in the apparatus of the present invention to produce cigarettes with dense ends.

DESCRIPTION OF THE PREFERRED EMBODIMENTS

The apparatus of FIGS. 1 and 2 comprises three conveyor means including a first conveyor means 13, a second conveyor means 3, and a third conveyor means 22. The conveyor means 3 is constituted by an endless belt having a horizontal or nearly horizontal upper stringer which supplies tobacco to the conveyor means 13. The belt 3 is mounted in a frame 1 and is trained around guide rollers 2 and 2a. The upper stringer of the belt 3 receives tobacco shreds in the form of a shower which is discharged by a suitable distributor 4 of conventional construction. The thus deposited tobacco shreds form on the upper stringer a continuous travelling mass 5 the thickness or cross section of which exceeds considerably the desired cross section of the tobacco rod. The upper stringer of the belt 3 is preferably flanked by suit-

able guide rails (not shown) to maintain the width of the travelling mass 5 within desired limits so that the cross-sectional outline of the mass 5 resembles somewhat the outline of the filler rod which is to be formed on the conveyor means 13.

The conveyor means 13 is constituted by a suction wheel which is rotatable about the horizontal axis of a driven shaft 42 and is formed with a circumferential tobacco receiving groove 16 whose bottom wall is constituted by an annular foraminous member 15. The wheel 13 is located in a vertical plane and, as shown in FIG. 2, comprises two axially spaced disk-shaped flanges 13a, 13b held apart by spacer members 14. The foraminous member 15 can be constituted by a length of air-permeable tape and is clamped or otherwise secured between the flanges 13a, 13b so that its axis coincides with the axis of the shaft 42. The radially outermost portions of the flanges 13a, 13b form the side walls of the groove 16. The cross-sectional area of the groove 16 is of rectangular outline and exceeds somewhat the cross-sectional area of the desired filler rod. The space within the foraminous member 15 and between the flanges 13a, 13b accommodates a stationary suction chamber 18 which is bounded by two radially extending walls 17, 17a. A compressed air chamber 19 is also provided between the flanges 13a, 13b within the confines of the foraminous member 15 and extends into the region below the uppermost part of the groove 16. Suction in the chamber 18 will be felt in the adjoining portion of the groove 16, i.e., this chamber will cause a current of air to flow across the adjoining part of the groove 16 and inwardly through the foraminous member 15. The chamber 19 discharges compressed air through the adjoining portion of the foraminous member 15 and through the groove 16.

The trimming means of the apparatus shown in FIGS. 1 and 2 comprises a brush-like rotary trimmer 20 which is adjacent to the guide roller 2 for the belt 3 and is placed near the periphery of the suction wheel 13 to level or equalize the exposed surface of the tobacco stream which travels with the groove 16 along the suction chamber 18 and on toward the chamber 19. A portion of the tobacco mass 5 enters the lowermost part of the groove 16 and forms therein a stream which leaves the wheel 13 at the upper end thereof, i.e., the stream travels with the wheel 13 through an angle of substantially 180 degrees. The filler rod which is obtained by equalizing the stream by means of the trimmer 20 is expelled from the groove 16 by compressed air issuing from the chamber 19, and such filler rod is then transferred onto the third conveyor means 22 which includes a second endless belt. The filler rod advances with the horizontal upper stringer of the belt 22 and is wrapped into a web or wrapper P of cigarette paper during travel through a wrapping mechanism 21 which is adjacent to the belt 22. The web P is fed onto the upper stringer of the belt 22 through a gap between the upstream end turn of this belt and the suction wheel 13. This gap further accommodates a stationary transfer member or stripper 26 which extends into the groove 16 immediately downstream of the wall 17a to positively separate from the foraminous member 15 any such tobacco particles which failed to leave the groove 16 under the action of compressed air issuing from the chamber 19. The transfer member 26 cooperates with a second transfer member 25 here shown as an endless belt made of spring steel or the like and trained around two pulleys so that its lower stringer engages the tobacco filler rod from above while successive increments of the filler rod advance from the groove 16 onto the tape P on the upper stringer of the belt 22.

That portion of the tobacco mass 5 which is not retained in the groove 16 by suction continues to travel with the belt 3 and is held against the lower stringer of the belt 3 by an endless retaining belt 12 trained around guide rollers 7, 8, 9, 10 and 11. Such tobacco is further

confined by flanges 6, 6a which are mounted on the shafts 31, 37 of the guide rollers 2, 2a.

The drive means of the apparatus shown in FIGS. 1 and 2 is illustrated in FIGS. 9 and 10. Such drive means includes the shaft 31 which is directly connected with the roller 2 and is driven by a variable-speed motor or transmission 30. The shaft 37 of the guide roller 2a carries a helical gear 36 which meshes with a helical gear 35 provided at one end of a shaft 34. The other end of the shaft 34 carries a helical gear 33 which meshes with a helical gear 32 on the shaft 31. The shaft 34 is journaled in bearing blocks L1, L2 carried by the base plate G of the frame 1.

The base plate G carries a supporting block St for the shaft 42 of the suction wheel 13. The shaft 42 receives motion from the shaft 31 through a gear train 38, 39, 40, 41. The gear 39 is mounted on a shaft 43 which is journaled in two upstanding walls G1, G2 carried by the base plate G. The gear 40 of the aforementioned gear train is mounted on a shaft 44 which is mounted in the wall G1. The shaft 42 is journaled in the support St and in the walls G1, G2.

The trimmer 20 is driven by the shaft 43 which carries a helical gear 45 meshing with a gear 46 on a shaft 47. The shaft 47 drives a vertical shaft 50 through a pair of mating bevel gears 48, 49, and the shaft 50 drives the shaft 53 of the trimmer 20 through a further pair of bevel gears 51, 52. The shafts 47 and 50 are journaled in bearing blocks 55, 56 which are mounted on the wall G2. The shaft 53 is journaled directly in the wall G2.

The operation of the apparatus shown in FIGS. 1, 2, 9 and 10 is as follows:

The distributor 4 showers tobacco shreds onto the upper stringer of the belt 3 whereon such shreds form a mass 5 whose cross-sectional area exceeds considerably the cross-sectional area of the filler rod. The mass 5 is conveyed toward the roller 2 by the upper stringer of the belt 3. The top portion of the mass 5 is sucked into the lowermost part of the groove 16 in the region above the roller 2 to form therein a tobacco stream which is attracted to the foraminous member 15 by a current of air drawn into the suction chamber 18. The lower portion of the mass 5 travels around the roller 2 between the flanges 6 and is conveyed back to the region below the distributor 4. During travel with the lower stringer of the belt 3, the remainder of the mass 5 is held from below by the retaining belt 12.

The suction wheel 13 takes from the mass 5 such amounts of shredded tobacco that the groove 16 is completely filled and that a portion of the resulting stream extends beyond the groove and into the range of substantially radially extending trimming elements of the trimmer 20. This trimmer equalizes the stream in the groove 16 while such stream preferably undergoes at least some compression by the current of air flowing across the groove 16 and radially inwardly through the apertures of the foraminous member 15. As shown in FIG. 3, the brush-like trimmer 20 can be replaced by a rotary disk-shaped knife or trimmer 20a which is driven to rotate in a horizontal plane and whose cutting edge removes surplus tobacco in the region between the lowermost part of the suction wheel 13 and the roller 2. The knife 20a is fixed to a vertical shaft 59 which receives motion from the shaft 34. Regardless of the exact nature of the trimming means, such trimming means converts the tobacco stream into a filler rod of constant cross section (see FIG. 2). When an increment of the filler rod reaches the stationary radial wall 17a which separates the suction chamber 18 from the chamber 19, such increment is caused to leave the groove 16 under the influence of compressed air issuing from the chamber 19 and also by the mechanical action of the transfer member 26 which extends into the uppermost part of the groove 16. The filler rod is caused to advance onto the web P on the upper stringer of the belt 22 and is wrapped into such

web during travel through the wrapping mechanism 21. Air issuing from the chamber 19 expels from the groove 16 any such tobacco particles which remain in the groove downstream of the transfer member 25 so that each increment of the groove which approaches the roller 2 is completely free of tobacco particles. The member 26 cooperates with the member 25 to effect orderly transfer of the filler rod onto the web P. Surplus removed by the rotary elements of the trimmer 20 descends onto the retaining belt 12 and is added to the remainder of the mass 5. This remainder of the mass 5 forms a reserve or cushion which circulates with the belt 3 and compensates for irregularities in the rate at which the distributor 4 showers tobacco shreds onto the upper stringer of the belt 3. The circulating tobacco cushion also effects some mixing of tobacco particles.

The distributor 4 is adjusted in such a way that, on the average, the amount of tobacco showered onto the belt 3 equals the amount of tobacco which is drawn into the groove 16 of the suction wheel 13. In other words, the amount of tobacco which forms a cushion and circulates with the belt 3 remains substantially constant. As a result of the manner in which a portion of the mass 5 is transferred into the groove 16 and of the equalizing action of the trimmer 20, the filler rod which advances with the suction wheel 13 beyond the trimmer 20 is of constant density and of uniform cross section. Thus, cigarettes obtained by severing of the wrapped tobacco filler rod downstream of the wrapping mechanism 21 will have the same weight.

FIGS. 4 and 5 illustrate a modified apparatus wherein a tobacco mass 105 is formed at a level below the lower stringer of an endless belt 103 corresponding substantially to the belt 3 of FIG. 1. The lower stringer of the belt 103 is trained around pairs of guide rollers 127 which are spaced from and are mounted at a level above the lower stringer of an endless retaining belt 112 corresponding to the belt 12 of FIG. 1. The lower stringer of the belt 103 is spaced from the lower stringer of the belt 112 and the distributor 104 showers tobacco shreds onto the lower stringer of the belt 112. The thus showered tobacco is deposited on top of the cushion which circulates with the belts 103, 112 and forms with the cushion a mass 105 which is conveyed toward the lower part of the suction wheel 113. This suction wheel has a circumferential groove 116 and accommodates a suction chamber 118.

An important advantage of the apparatus shown in FIGS. 4 and 5 is that the shreds are thoroughly mixed and that each shred leaves the belts 103, 112 not later than after having completed a full cycle in the path defined by the belts 103, 112. The same holds true for surplus tobacco which is removed by a rotary trimmer 120. This trimmer removes the surplus from the stream which is drawn into the groove 116 by the air current produced by suction chamber 118. The surplus drops into the space between the belts 103, 112 and advances with the cushion toward the distributor 104. The manner in which the filler rod is transferred from the suction wheel 113 onto the upper stringer of the belt which cooperates with the wrapping mechanism is the same as described in connection with FIGS. 1 and 2.

The belt 112 is trained around flanges 129 which are concentric with guide rollers 127 for the belt 103 and around flanges 106a which are concentric with the roller 102a. The surface of the tobacco stream in the groove 116 of the suction wheel 113 is trimmed immediately after such stream enters the groove because the orbiting trimming elements of the trimmer 120 are closely adjacent to the guide roller 102.

It is often desirable to subject the tobacco stream in the groove 116 to at least some mechanical compression. Such mechanical compression can be carried out at the point where the tobacco stream enters the groove 16 or 116, for example, by reducing the gap between the pe-

riphery of the suction wheel 13 or 113 and the upper stringer of the belt 3 or 103 in such a way that the stream which is separated from the mass 5 or 105 necessarily undergoes mechanical compression which is produced by the belt 3 or 103 and the foraminous member which forms the bottom wall of the groove 16 or 116. Furthermore, the stream in the groove 16 or 116 can be compacted by pneumatic means, i.e., by regulating suction in the chamber 18 or 118 in such a way that the currents of air flowing across the groove 16 or 116 and through the foraminous member will effect necessary compression of the tobacco stream. If the suction in chamber 18 or 118 is varied intermittently, the tobacco stream in the groove 16 or 116 will comprise denser portions which alternate with less dense portions. Dense portions will be formed by such sections of the stream in the groove 16 or 116 which are located between the wheel 13 or 113 and the roller 2 or 102 when the suction in chamber 18 or 118 is increased. By resorting to such method, one can obtain cigarettes wherein the ends of the tobacco filler are denser than the intermediate part of the filler. The trimmer 120 of FIG. 4 is adjacent to a portion of the groove 116 which accommodates strongly compacted tobacco when the suction in chamber 118 increases. It is also possible to provide a separate suction chamber opposite the trimmer 120 and to use the suction chamber 118 solely as a means to hold the filler rod in the groove 116 during travel toward the upper part of the wheel 113. Suction in the separate suction chamber is then increased at regular intervals to compact such portions of the tobacco stream which are to form the ends of fillers in finished cigarettes.

Cigarettes with dense filler ends can in another way be obtained by resorting to the structure which is shown in FIG. 11. The inner sides of the flanges 13a, 13b are formed with registering recesses so that the width of the groove which surrounds the foraminous member 15 varies at regular intervals, as seen in the circumferential direction of the suction wheel 13. The enlarged portions of the groove will receive more tobacco and the filler rod leaving the suction wheel 13 will comprise portions of greater cross section alternating with portions of smaller cross section. In the wrapping mechanism 21 (FIG. 1), the filler rod is compressed to form with the web P a wrapped cigarette rod of constant cross section whereby the density of the filler in such cigarette rod varies. If the cigarette rod is severed across the denser portion of its filler, the filler of each cigarette will have at least one dense end to reduce the likelihood of tobacco fallout.

As shown in FIG. 6, the suction wheel 13 can cooperate with a mechanical compacting member 21a which compacts tobacco in the groove 16. The member 21 is constituted by a roller which enters the groove 16 and the distance *a* between the axis of the roller 21a and the axis of the suction wheel 13 may be varied to select the desired compacting action for a given tobacco stream.

FIG. 7 illustrates that the roller-shaped compacting member 21a of FIG. 6 may be replaced with a stationary compacting member 22a which resembles a runner and extends into the groove 16 to compact the tobacco stream by pressing it against the foraminous member 15. The main portion of the compacting member 22a is substantially parallel to the adjoining portion of the foraminous member 15. This member 22a may be adjusted in a direction toward or away from the axis of the suction wheel 13.

Referring finally to FIG. 8, there is shown an additional trimmer 23 which is rotatable about a horizontal axis and comprises substantially radially arranged trimming elements which extend into the groove 16 to subject a coarsely trimmed tobacco stream to a second trimming or equalizing action. The trimmer 23 may be constituted by a brush or the like and reduces the height *H* of the coarsely trimmed stream to a height *h* which is the height of the filler rod. For example, the trimmer 23 can be disposed downstream of the trimmer 20 of FIG. 1 or

downstream of the trimmer 20a shown in FIG. 3. The trimmer 20a removes all such surplus which extends beyond the groove 16 so as to form a coarsely trimmed stream having a height H, and the trimmer 23 thereupon removes the remaining surplus by reducing the height of the travelling tobacco body from H to h. In other words, the trimmer 20 or 20a can be said to constitute a coarse trimmer and the trimmer 23 of FIG. 8 is a second or fine trimmer. The distance b between the axes of the trimmer 23 and suction wheel 13 is adjustable, and the width of trimming elements on the trimmer 23 preferably equals the width of the groove 16, i.e., the distance between the flanges 13a, 13b of the suction wheel.

Without further analysis, the foregoing will so fully reveal the gist of the present invention that others can, by applying current knowledge, readily adapt it for various applications without omitting features which fairly constitute essential characteristics of the generic and specific aspects of my contribution to the art.

What is claimed as new and desired to be protected by Letters Patent is set forth in the appended claims.

I claim:

1. Apparatus for producing a wrapped tobacco rod, comprising first conveyor means having a tobacco receiving groove, a foraminous member constituting the bottom wall of said groove, and a suction chamber adjacent to said foraminous member opposite said groove to draw a current of air across said groove and through said foraminous member; second conveyor means for supplying to said groove a continuous tobacco stream each unit length of which contains a surplus of tobacco over that in a unit length of the tobacco rod; a first trimmer adjacent to said groove for bodily removing some of said surplus from the tobacco stream; a second trimmer adjacent to said groove downstream of said first trimmer for bodily removing the remainder of said surplus from the stream so that the thus trimmed stream forms a continuous filler rod; third conveyor means for receiving said filler rod from said first conveyor means; and means for applying a wrapper to the filler rod after the filler rod leaves said first conveyor means.

2. Apparatus as set forth in claim 1 wherein said second trimmer extends into said groove.

3. Apparatus as set forth in claim 1, wherein said first conveyor means comprises a wheel rotatable about a horizontal axis and said groove is provided in the circumference of said wheel.

4. Apparatus as set forth in claim 3, wherein said wheel comprises an uppermost portion and a lowermost portion, wherein said tobacco stream enters said groove in the region of one of said portions, and wherein said filler rod leaves said groove in the region of the other portion of said wheel.

5. Apparatus as set forth in claim 1, wherein each of said second and third conveyor means comprises an endless belt having a substantially horizontal upper stringer respectively arranged to supply the tobacco stream to and to receive the filler rod from said groove.

5 6. Apparatus as set forth in claim 1, wherein one of said trimmers comprises a rotary body having a predetermined axis of rotation and a plurality of tobacco removing elements extending substantially radially of and outwardly from said rotary body.

7. Apparatus as set forth in claim 1, wherein said suction chamber extends substantially to the region where the filler rod leaves the groove of said first conveyor means.

10 8. Apparatus as defined in claim 1, further comprising mechanical compacting means for the tobacco stream in said groove.

15 9. Apparatus for producing a wrapped tobacco rod, comprising first conveyor means having a tobacco receiving groove, a foraminous member constituting the bottom wall of said groove, and a suction chamber adjacent to said foraminous member opposite said groove to draw a current of air across said groove and through said foraminous member; means for supplying to said groove a tobacco stream which contains a surplus of tobacco over that in the tobacco rod; mechanical compacting means for compacting the stream in said groove; trimmer means for bodily removing the surplus from the compacted tobacco stream in said groove so that the trimmed stream forms a filler rod; second conveyor means for receiving the filler rod from said first conveyor means; and means for applying a wrapper to the filler rod after the filler rod leaves said first conveyor means.

20 10. Apparatus as set forth in claim 9, wherein said trimmer means comprises a plurality of trimmers arranged to remove said surplus in successive stages.
